Fig. 8.

This technical drawing illustrates a mechanical assembly, likely a component of a larger machine. The drawing is a line drawing with various parts labeled with numbers:

- Top row: 84 16, 84 18, 84 18, 70, 85, 84 17.
- Second row: 85, 25, 85, 25.
- Third row: 10, 11, 10, 11.
- Fourth row: 10, 11.
- Left side: 31 50.
- Middle section: 31 50, 33, 31, 32.
- Bottom left: 31.
- Bottom right: 31.
- Bottom center: 32.
- Bottom left corner: 31.
- Bottom right corner: 31.

The assembly features a central vertical structure with horizontal plates and various mechanical details. The labels are handwritten-style numbers.

UNITED STATES PATENT OFFICE.

JOHN BRICKEN, OF CHICAGO, ILLINOIS, ASSIGNOR, BY MESNE ASSIGNMENTS, TO THE WAHL COMPANY, OF WILMINGTON, DELAWARE, A CORPORATION OF DELAWARE.

CALCULATING-MACHINE.

1,334,278.

Specification of Letters Patent. Patented Mar. 23, 1920.

Application filed December 15, 1918. Serial No. 806,821.

To all whom it may concern:

Be it known that I, JOHN BRICKEN, a subject of the Emperor of Russia, residing at Chicago, in the county of Cook and State of Illinois, have invented a certain new and useful Improvement in Calculating-Machines, of which the following is a specification.

My invention relates to calculating machines particularly those which are associated with a typewriter. A good example of this class of machine is shown and described in the issued patent to John C. Wahl, No. 893,719, dated July 21, 1908.

My present machine has some of its parts similar in structure to the machine described in the above cited patent, and has the same general mode of operation, viz., on the carriage of the typewriter is mounted a totalizer in which numbers are inserted *seriatim* by an actuating mechanism rigid with the typewriter frame.

While my actuating mechanism is similar in part to that shown in the above cited Wahl patent, the totalizer and carrying mechanism constituting my present invention are a wide departure from the Wahl structure.

One of the objects of my invention is to provide a calculating machine having but a single carrying mechanism, regardless of the number of totalizers which are employed. Each totalizer consists of but a single set of gear wheels which are provided with the customary number wheels and a mechanism to transfer the tens from one gear to another is located in the actuator. This transfer mechanism is adapted to coöperate with any totalizer so that in the case of a calculating machine employing a plurality of totalizers, but one transfer mechanism is required for the plurality instead of having an individual transfer mechanism associated with each totalizer as is the usual practice.

A further object of my invention is the provision of an improved form of actuating mechanism which is so interlocked with the transfer mechanism as to prevent overthrow of the latter.

A further object of my invention is the provision of improved means to eliminate the spiral effect occurring when the carry-

ing chain extends over more than one or two decimal places.

A further object of my invention is the provision of a combined totalizer and carriage lock.

A further object of my invention is the provision of novel means for preventing overthrow of the transfer pinions as these pinions are brought into the action of carrying.

A further object of my invention is the provision of means to prevent actuation of the first transfer pinion when the totalizer is violently returned to zero.

These and further objects of my invention will be disclosed and referred to hereafter in the specification and claims.

Referring now to the figures,

Fig. 1 is a section along line 1—1 of Fig. 2.

Fig. 2 is a section along line 2—2 of Fig. 1.

Fig. 3 is a section along line 3—3 of Fig. 2.

Fig. 4 is a section along line 4—4 of Fig. 2.

Fig. 5 is a developed view of the gearing.

Figs. 6 and 7 are successive positions of the carrying and transfer gears during the operation of transferring the tens.

Fig. 8 is a right elevation of my invention as applied to the Remington typewriter.

Fig. 9 is a front elevation of my invention as applied to the Remington typewriter.

I shall divide the description of my invention into several heads, and describe the several mechanisms necessary to form the complete machine separately.

First—The totalizer.

The totalizer consists of two side plates 10 and 11, which are mounted on a truck 12, connected to and moving with the typewriter carriage 84. These plates are held the proper distance apart by shafts 13, 14 and 15, secured rigidly between the plates. The side plates 10 and 11 are dovetailed to be supported on the corresponding dovetail on the truck 12 (see Figs. 2 and 8). A latch 16 pivotally mounted on a stud 17 in the side plate 11 and controlled by a finger piece 18 mounted on a stud 19 in the same side plate, engages the beveled surface on the back of the truck 12, thus serving to hold the to-

talizer rigid at any desired place on the said truck. Rotatably mounted on a shaft 15 are the carrying gears 20 each of which is provided with two carrying teeth 21. 5 Rotatably mounted on the shaft 14 is a set of idle gears 86 which serve to transmit the motion of the carrying gears 20 to a set of gears 22, rigidly attached to the number disks 23, these disks and gears being rotatably mounted on the shaft 13.

10 A set of division plates 87 supported on the shafts 14 and 15 serve to separate adjacent gears 20 and 86 thus preventing the rotation of gears 20 and 86 in one decimal section being communicated by friction to the same wheels in adjacent decimal sections. The shaft 13 on which are mounted the number disks 23 has in it a small key way 88 which serves to prevent from rotation the 15 separating washers 89, placed between each of the number disks 23. These washers have small tangties which engage the key way, and thus prevent the motion of one number disk 23 from being communicated by friction to number disks in adjacent places.

20 A suitable cover 24 having a window 25 serves to protect the interior of the totalizer and mask the numbers on the disks except the ones opposite the window 25.

25 30 Pivotaly mounted at 26 between the side plates 10 and 11 is a universal lock 27 having a cam 28 extending the entire space between the side plates 10 and 11, and adapted to engage all of the carrying gears 20. A 35 spring 29 between the lock 27 and a bar 90 extending between the side plates serves to maintain the lock 27 in the position shown in Fig. 2.

30 The carrying gears 20 have twenty teeth 40 and two carrying teeth 21. These carrying teeth are in a different plane from the gear 20 itself, but are rigidly attached thereto. Numbers are inserted in the totalizer *seriatim* by a master wheel 30 rotatably mounted in the framework, the totalizer escaping one step to the left after the insertion of each 45 digit of the number by the master wheel. The lock 27 is removed from its contact with the carrying gears 20 during the insertion of each number and the master wheel 30 is rotated by operation of numeral keys 32 by means which will afterward be described.

Second—The actuator.

55 As before remarked the actuator is somewhat similar to that shown in the cited patent to Wahl. Reference to Figs. 1 and 2 will show that a pull rod 31 connects each of 60 the typewriter numeral keys 32 to a cam shaped piece 33, rotatably mounted on a shaft 34, rigid in the framework. Operation of the typewriter key results in the downward motion of the pull rod 31, and

consequent rotation in a counter clockwise direction of the cam 33.

I wish now to call attention to two functions of the cam 33. Rotation of the cam first results in some preliminary operations such as placing the actuator and totalizer in a position to permit differential rotation of the master wheel and then in the rotation of the master wheel which rotation depends in amount on the particular pull rod 31 which has been actuated. I shall first describe the 75 preliminary operation.

Each of the cams 33 has a cam-shaped surface 35 adapted to engage a universal roller 36 attached by crank arms 37 to the rock shaft 38 rotatably mounted in the 80 framework. As any cam 33 rotates in a counter clockwise direction, the engagement of the cam 35 with the roller 36 results in clockwise rotation of the rock shaft until the roller 36 has traveled to the concentric surface of the cam 35. Rigid with the rock shaft 38 is a helical cam 39 (best shown in Fig. 1) operating in a slot 40 in a piece 41 slidably mounted in the framework. On a shaft 42 rotatably mounted in the framework, which shaft I shall hereafter call the sector shaft, is mounted a sector 43 swinging about a pivot 44. This sector 43 is so mounted on the pivot 44 in a block 45 rigid with the sector shaft 42 that it has no rotation in relation to the sector shaft 42 but may have motion in a plane parallel to said shaft about its pivot 44. The normal position of the sector 43 is the position shown in Fig. 1, viz., out of engagement with master 95 wheel gears presently to be described. Rotation of the rock shaft 38 and of the helical cam 40 rigid with it results in the shifting of the sliding piece 41, Fig. 1, to the left, and consequent movement of the sector 43 to a 100 position perpendicular to the sector shaft 42. 105

Thus far I have described one of the preliminary operations necessary for a rotation of the master wheel. However, there is another preliminary operation which it will be 110 best to describe at this point, viz., the unlocking of the master wheel and carrying gears 20 and the locking of the totalizer to the actuator framework during the rotation of the master wheel 30.

115 Fulcrumed on the shaft 46 in the framework is a master dog 47. An arm 48 rigid with the rock shaft 38 has a roller 49 which engages a slot 50 in the tail of the master dog 47. The master dog is shown in its 120 normal position in Fig. 2, and reference thereto will disclose that the slot 50 has its lower portion concentric with the rock shaft 38, and its upper portion approximately vertical. From this it follows that rotation 125 of the rock shaft 38 in a clockwise direction will result in rotation of the master dog 47 in a clockwise direction about its fulcrum 46.

The upper end of the master dog has three distinct functions. First, the cam 51 dogs the teeth of the master wheel 30. Second, a fork 52 engages the lock 27 withdrawing the cam 28 from the carrying gears 20 of the totalizer. Third, a tooth 53 engages between the teeth of a rack 54 rigidly mounted to the truck 12, thus locking the truck rigid to the actuator framework as long as the dog 47 is in its displaced position. It will be remembered that the operation of any numeral key 32 results in the clockwise rotation of the rock shaft 38. In addition to the above recited functions of the master dog, there is a function connected with the transfer gears which will be referred to hereafter.

I will now describe the means by which the master wheel 30 is rotated the number 20 of teeth depending on the numeral key actuated.

Loosely mounted on the shaft 34 is a series of goosenecks 55, one for each cam 33. Rigidly mounted in each gooseneck 55 is a pin 56 which cooperates with a slot 57 in the cam 33. Rotation of the cam 33 will first rotate the rock shaft 38 until the roller 36 is on the dead surface of the cam 35, then the right side of the slot 57 will engage the pin 30 56, and carry the gooseneck with it during the remainder of the motion of the cam 33.

Rigidly mounted on the sector shaft 42 is a series of arms 58, having rollers 59 mounted thereon, which arms are engaged by the 35 goosenecks 55 as shown in Fig. 2 and rotated thereby until said rollers 59 are in the concentric slots of the goosenecks. These arms 58 are so arranged on the sector shaft 42 that the actuation of different goosenecks 40 will result in different degrees of rotation of the said shaft. There is a gooseneck 55 for each numeral key 32 of the typewriter, and the arms are so arranged that actuation of any key will result through the action 45 of its associated gooseneck on an arm 58 in rotation of the sector 43 the required amount.

The sector 43 may engage with the gear 60, slidably but non-rotatably mounted on 50 a shaft 62 rotating in the framework (best shown in Fig. 3). The master wheel 30 is rigid with the shaft 62 and has a yoke 92, arranged to engage a similar yoke 93 rigid with the gear 60. Thus any rotation of the 55 gear 60 results in an equal rotation of the master wheel 30. Meshing with the gear 60 is a gear 61 rotatably but non-slidably mounted on a shaft 63. The gears 60 and 61, and the shaft 63 correspond in position 60 and functions to the gears 52 and 56 and the shaft 54 in the cited patent to Wahl.

Reference to this patent will show clearly how the shifting of the shaft 54 therein (corresponding to the shaft 63 in Fig. 3 of

this application) determines the direction of 65 rotation of the master wheel 30, and I shall not enter into a full description of this particular part of the actuator in this place.

Third—The transfer mechanism.

Rotatably mounted on a shaft 64 rigid in the framework is a set of transfer gears 65. Each of these gears has a set of long teeth 66, and short teeth 67. A series of plates 75 95 supported by two pillars 96 rigid in the framework separate these transfer gears 65 from each other, thus preventing motion of one being transferred by friction to the adjacent ones on either side. These plates 95 perform the same function as the plates 87 80 and the washers 89 before referred to.

Fig. 5 shows clearly the lateral relation of the transfer gears 65 to the carrying gears 20. The first transfer gear 65 to the right in Fig. 3, which gear I shall hereinafter refer to as the first transfer gear, is in a position to have its short teeth engaged by carrying teeth 21 of the carrying gear 20 in engagement with the master wheel. The long teeth 66 of this first transfer gear 65 90 engage with the next carrying gear 20 to the left. The carrying teeth 21 of this second carrying gear engages the short teeth 67 of the second transfer gear 65, whose long teeth 66 engage the next carrying gear 95 to the left. This arrangement continues through the entire length of the totalizer, carrying gears 65 being sufficient in number to accommodate the widest totalizer used on the machine. It will be remembered that 100 the totalizer moves relatively to the actuating mechanism, and hence relatively to the transfer gears which are rigid in the same framework. Consequently all the carrying gears 20 to the left of the master wheel in 105 any totalizer engaged by the master wheel 30 have associated with them a transfer gear 65, and if the rotation of the master wheel 30 entails any carrying there will be a carrying chain extending through that portion of 110 the totalizer which is to the left of the master wheel.

Numbers are inserted in the totalizer one digit at a time, beginning with the digit in the highest order. Since any carrying gear 115 20 to the right of the master wheel is in a lower order than the digit which is being inserted, such carrying gears 20 need have no transfer gears with them for they are never moved during such insertion. As the 120 totalizer progresses from right to left, during the insertion of the digits of the number, the carrying chain of course becomes continually longer as additional transfer gears 65 are engaged by the totalizer as it 125 moves step by step to the left.

The arrangement of the transfer gears just described entails several difficulties.

First, owing to the spiral effect always present when carrying is done through a chain of transfer gears, the motion of the totalizer gears 20 through the transfer gears may be interfered with, as it is necessary for these transfer gears to be alined into their proper position before the carriage escapes.

Second, owing to the fact of the transfer gears and the carrying gears of the totalizer being relatively movable to each other, it is practically impossible to provide the carrying gears 20 with a locking surface such as is shown in the carrying gears of the cited patent to Wahl for instance.

Third, assuming the totalizer to have a 9 in the decimal place in contact with the master wheel and assuming that one wishes to subtract this 9 from the totalizer thus bringing the totalizer to zero, it is possible to move the first transfer gear, and perhaps some of the others, to the left by a violent manipulation of the 9 key. This is because rotation of the carrying gear 20, engaged with the master wheel back to its zero position, will bring the carrying tooth 21 associated with said gear up to contact with the first transfer gear. Now, if there is any lost motion between the master wheel and the carrying gear 20 engaged with it, the carrying tooth 21 will give the first transfer gear a blow and this blow may be communicated through the entire carrying chain to the left, since by hypothesis, all of the gears 20 to the left, being in their zero position, have their carrying teeth 21 in contact with a transfer gear 65. Therefore it is necessary to provide mechanism to avoid the difficulties just mentioned, and such mechanism I shall now proceed to describe.

First, mechanism to remove the spiral effect occurring consequent to the operation of the transfer gears is as follows:

Pivoted in the framework at 68 is an aliner cam 69 which has a cam surface 70 adapted to coöperate with all the transfer gears (best shown in Fig. 4). A spring 97 tends to rotate the cam 69 in a clockwise direction. The cam surface 70 is adapted to enter between the teeth of the transfer gears 65, which have deeply cut teeth (Figs. 2, 4, 6 and 7) and thus aline them. This cam surface 70 is made somewhat in the shape of a wedge, for when there is a spiral effect, the displacement between two adjacent gears is small compared to the displacement between the gears at the beginning and the end of the chain.

The aliner cam 69 has rigid with it an arm 71, which is connected by a link 72 to the master dog 47. Consequently during the movement of this master dog the aliner cam will be entirely withdrawn from the transfer gears. On its return to its normal position it will first engage the second transfer

gear counting from the right (shown best in 65 Fig. 4), then the next and so on, the gear on the extreme left being engaged last. Since the first transfer gear cannot be much out of its position, the action of the cam 70 on these gears will bring them into the proper 70 alinement by the time the master dog has returned to its normal position, as shown in Fig. 2. The carriage then escapes to the next decimal place.

Second, I shall now describe the means of 75 preventing overthrow of the transfer gears.

Coöoperating with the first and several arbitrarily selected transfer gears is a series of cams 79. These are rotatably mounted on a shaft 80, rigid in the framework, and are 80 held in their normal positions as shown in Fig. 2 by springs 81. Considering for the present but one of these cams, the one associated with the first transfer gear 65 as shown in Fig. 2, it will be seen that it is provided with two notches 82 and 83, and that these notches are so spaced that movement of the coöoperating transfer gear 65 in either direction will result in a displacement of the cam as shown in Figs. 6 and 7.

Inspection of these figures shows that if the transfer gear 65, shown in Fig. 6, for instance, is rotated in a clockwise direction, the long teeth 66 will displace the cam 79 until the tooth is free from the notch 82. 95 However, since the surface of the cam 79 to the left of this tooth has no notch, it will be impossible for the transfer gear 65 to rotate another tooth until the cam 79 has been returned to its normal position by means of 100 the spring 81. By the time this has occurred, any momentum which the transfer gear 65 may have had has been destroyed. Therefore it is impossible for this transfer gear 65 to move more than one tooth until 105 the cam 79 has been returned to its normal position. Preventing the transfer gear 65 from moving more than one tooth will prevent the carrying gear 20 of the totalizer in mesh with it from moving more than one 110 tooth, also, and since in any totalizer, no gear to the right of the master wheel is required to move more than one tooth for a single actuation of the master wheel, thus limiting of the motion of these gears to but 115 one tooth will not interfere with the action of the totalizer.

Third, I shall now describe mechanism for preventing motion of the first transfer gear when a carrying tooth 21 is violently 120 brought into contact with such transfer gear, and does not pass through it to carry.

Fulcrumed in the framework at 73 is a pair of arms 74 and 75 connected by a rigid post 76, and supporting between them at 125 their upper ends a roller 77 adapted to engage with the first transfer gear 65 (Figs. 2, 3 and 4). Between the lower ends of these

arms 74 and 75 is supported a roller 78 adapted to contact with the tooth of the master wheel 30. By reference to Fig. 2, it will be seen that the master wheel 30, its 5 engaged carrying gear 20 and the first transfer gear 65, form a chain of gearing, and that the rollers 77 and 78 are so placed that rotation of the master wheel will result in oscillation of the framework, consisting of 10 the arms 74 and 75, about its fulcrum 73.

Now, when the carrying tooth 21 is brought into contact with one of the teeth of the first transfer gear, the master wheel 30, by hypothesis, is stopped in the position shown 15 in Fig. 2, that is, with one of its teeth in engagement with the roller 78. As long as this tooth is approximately in line with the roller 78, it will be impossible for the first transfer gear to move since the teeth of the 20 same are engaged by the roller 77. Therefore, even if the carrying tooth 21 does give a blow upon the transfer gear, said gear will be prevented by the roller 77 from moving. However, should the carrying tooth 21 after 25 having given the above recited blow continue to move through the transfer gear, as will be the case when the carrying gear 20 passes through zero, the tooth of the master 30 wheel shown in engagement with the roller 78 in Fig. 2 will, of course, progress to the left and the roller will be enabled to enter the hollow between this tooth and the next succeeding one, thereby allowing the first transfer gear to progress one tooth.

I consider the above described mechanism very important, since while in normal operation if the totalizer be brought to zero, no 35 tendency of the first transfer gear to move will be observed, yet it is always possible 40 by bringing the gear 20 to its normal position with great velocity to give a blow on the first transfer gear, and this blow will be communicated to the transfer gears to the left, and consequently the totalizer may be 45 made to overthrow if the mechanism just described is not present.

While I have described this action as occurring when the totalizer is brought from 9 to zero, it is obvious that it is present in 50 a lesser degree when the totalizer is brought from 8, 7 or even 6. The necessary condition for giving a hard blow is that the carrying gear 20 be moved a distance sufficient to acquire considerable momentum before its 55 carrying tooth makes contact with the associated gear.

The same effect may also be observed when the totalizer stands, for instance, at 99999990, and a 9 is added into the totalizer. 60 As in the previously recited case, the addition of this last number will bring all the carrying teeth 21 in contact with their associated transfer gears (but on the other side of the teeth,) and the same effect may

be observed in a reverse direction. My 65 mechanism just described completely overcomes this fault, since if the master wheel is stopped with a tooth in contact with the roller 78, it is impossible for the first transfer gear 70 to move, hence for any transfer gears to the left thereof to be disturbed from their normal position.

Fourth—General operation

Having thus described the machine in detail, I shall now describe its general operation.

The totalizers are supported on the truck 12, which is rigid with the carriage of the typewriter. Operations of the numeral keys 80 actuate the typewriter escapement in the well known way, and thus the carriage and the totalizers mounted on the truck 12 move step by step to the left as the numeral keys 85 are operated. Operation of any numeral key 32 results in the following sequence of operations:

(1) The master dog 47 which has been locking the master wheel against rotation is rotated in a clockwise direction, the cam 90 53 entering the rack 54, thereby locking the truck 12 to the actuator frame work, the extension 52 acting on the locking bar 27, thus unlocking all the carrying gears 20 of the totalizer, the sector 43 is engaged with either 95 the gear 60 or 99 (the gear 99 being rigid with the gear 61), according as addition or subtraction is to result from the operation of the numeral keys and the aliner 69 is withdrawn from the transfer gears 65. All 100 of these actions occur during the first part of the operation of the key during the time that the attached cam 33 is moving from the position shown in Fig. 2, into the position in which the right side of the slot 57 is in engagement with the pin 56. At this time the roller 36 of the rock shaft has reached the concentric surface of the cam 35.

(2) Further motion of the key results in the movement of the gooseneck 55 in a 110 counter clockwise direction thereby rotating the sector 43 and the master wheel 30, which at that time is geared thereto, a number of teeth depending upon the numeral key operated. During this time, if any carrying is 115 done, the carrying teeth 21 of the gear 20 will engage the first transfer gear 65, and rotate it through the space of one tooth as said tooth 21 passes through said gear. Other rotation of the first transfer gear 65 is prevented by action of the cam 79 on the long teeth 66 as previously described.

(3) As the numeral key is further depressed, the roller 36 which has been riding on the dead surface of the cam snaps back 125 into its normal position by the force of a spring 100 (Fig. 2) attached to an arm 101 rigid with said roller 36, thereby restoring

the master dog 47 to its normal position, the helical cam 39 to its normal position, resulting in the tilting of the sector 43 to the position shown in Fig. 1, and the return of the aliner cam 69 to its normal position as shown in Fig. 2, thereby lifting the transfer gears and consequently any carrying gears 20 which may be in mesh with them. The carriage of the typewriter now escapes, shifting all the carrying gears 20 one step to the left, thereby engaging an additional transfer gear at the left side of the totalizer, and bringing the new carrying gear 20 into mesh with the master wheel. On the return stroke of the key, the heel of the cam 35, which I have numbered 84 engages the left side of the roller 36, and thereby rotates the rock shaft 38 in a counter-clockwise direction. This extra rotation will not affect any of the parts just mentioned since the helical cam 39 has a dead surface on it, the roller 49 moves in the dead surface of the slot 50, and the other parts being connected to the master dog 47, of course, remain unmoved. When the cam 85 has reached its normal position the roller under the influence of the spring 100 snaps from the front surface of the cam 35 to its normal position. This completes the cycle of operation, and the totalizer is in a position for the insertion of the next digit of the number.

The actuator of my machine also includes a single key mechanism to prevent the operation of more than one key at a time and a full stroke mechanism to insure a key's being fully operated in case motion of said key is once initiated. Both of these mechanisms are well-known in the art, efficient forms adapted for use with the Wahl actuator are shown in the cited patent to Wahl to which reference may be had, and I will therefore not describe them here.

I have shown in Fig. 3 but four cams 79. While theoretically a cam 79 should be associated with each transfer gear, I have found in practice that this is unnecessary and that providing a cam 79 for every third gear of the transfer gears will be sufficient to prevent any overthrow.

Having now described my invention, I will call attention to some of its advantages.

The totalizer itself as is evident is extremely simple. It consists of but a set of carrying gears 20, and while I have shown the numbers on a separate wheel geared to the carrying gears 20, it is evident that this extra gearing comes from consideration of space only. The numbers may be put on disks rigidly attached to the gears 20 in case the device were used with a typewriter having a wide spacing instead of the usual tenth of an inch. A single universal lock 27 holds these gears 20 in their normal position. Consequently I may say that the totalizers

are of very cheap construction, and this is a great consideration in calculating machines requiring a large number of totalizers for calculations in which the numbers are arranged in a plurality of vertical columns.

Another great advantage of my invention is the provision of a single set of transfer gears adapted to co-operate *seriatim* with any totalizer which may be on the truck. It is evident that totalizers of varying width may be used on the same truck, since the transfer gears to the left of the totalizer do not come into use.

In case it should be desired to use two totalizers close together it is evident that the fact of a single space being occupied by the totalizer side plates will prevent any carrying from one totalizer into another totalizer to the right since the chain of gearing would be broken at the space occupied by the totalizer side plates.

In case it is desired to arrange the carrying gears of the totalizer so that there shall be a space corresponding to the decimal or pointing off space between them, all that is necessary is to make the carrying gear 20 occupying such space have twenty carrying teeth 21 instead of two, as shown. This will make such a wheel simply an idle wheel, and extend the carrying chain over the decimal or pointing off space.

I am aware that it has been proposed to make a common carrying mechanism co-operate with a number of totalizers arranged in a line, one for instance being that shown in the prior art. I wish to point out, however, the advantages that my structure has over prior structures. By making the carrying mechanism stationary, and the totalizers movable, I am able to dispose of the cumbersome cord connection shown in certain prior patents. Also since there are a number of parts of the actuating mechanism such as the aliner bars, etc., which are inseparably connected with the action of the carrying mechanism, by placing of the carrying mechanism on the frame and making the totalizer which, at best, consists of but a few gear wheels, movable, there results a much simpler structure than that of Wolfe.

Thus, I have the simplest element of my calculating machine the movable element. The more complex element is fixed to the frame and thereby avoids the necessity of moving this complex element synchronously with the carriage and carrying the key connection to this complex element.

Again, the form in which numbers are written on the work sheet is determined by the relative position of the totalizers to each other. By adjustably mounting my totalizers on the moving element instead of fixing them rigid in the framework as shown in the prior structure, I am able to easily ad-

just the machine to compute in a variety of forms, instead of being limited to one arrangement of the totalizers fixed in the framework.

5. I consider the means for preventing overthrow of the transfer gears of great importance since this is the first operative totalizer with which I am acquainted having a set of transfer gears moving relatively to the totalizer, and having means for the prevention of overthrow of said totalizer and I wish to claim the same broadly.

I believe I am the first to provide a totalizer having a set of transfer gears traveling relatively thereto, and means to bring said transfer and totalizer gears into correct alinement before the escaping of said totalizer to engage transfer gears in an additional decimal place and I wish to claim the same broadly.

Many changes and modifications may be made in the precise structure herein described without departing from the spirit of my invention since I claim:

25. 1. In a calculating machine, the combination of a frame, a traveling bar, a totalizer mounted on said bar, carrying mechanism mounted on said frame and adapted to coöperate with said totalizer in all of its decimal places and a set of numeral keys adapted to operate said carrying mechanism.

2. In a calculating machine, the combination of a frame, a traveling bar, a totalizer 35 adjustably mounted on said bar, a carrying mechanism mounted in said frame and adapted to coöperate with said totalizer in all of its decimal places, a set of numeral keys, and connections between said numeral 40 keys and said carrying mechanism whereby said carrying mechanism is operated by said numeral keys.

3. In a calculating machine, the combination of a frame, a bar traveling relatively 45 to said frame, a plurality of totalizers adjustably mounted on said bar, each of said totalizers including as one of its elements a plurality of gear wheels, a lock mounted in each totalizer for its associated set of 50 gear wheels, lock operating means, a carrying mechanism mounted on said frame, said carrying mechanism and lock-operating means being adapted to coöperate *seriatim* with all of said totalizers, whereby a single 55 carrying mechanism and lock-operating mechanism is common to a plurality of totalizers.

4. In a calculating machine, the combination of a frame, a traveling totalizer, a carrying mechanism mounted on said frame and adapted to coöperate with said totalizer in all of its decimal places, said carrying mechanism consisting of a plurality of members, one member for each decimal order, an

alining device for said carrying mechanism, 65 said alining device adapted to contact with said carrying mechanism element of lower order before contacting with the carrying mechanism of higher order, a set of keys adapted to insert numbers in said totalizer 70 and means operated by said keys to actuate said alining device.

5. In a calculating machine the combination of a frame, a traveling totalizer, a set of keys to insert numbers in said totalizer, 75 a carrying mechanism on said frame said carrying mechanism consisting of a plurality of elements one for each decimal order and any of said elements being adapted to coöperate with said totalizer in all of its 80 decimal places, and means to aline said carrying mechanism operated by any of said keys said alining means being so constructed that when it is brought into operation by the action of any of said keys said alining 85 mechanism will first operate on the element of the carrying mechanism in the lower decimal order and subsequently operate on the elements of the carrying mechanism in higher decimal orders.

6. In a calculating machine the combination of: a set of numeral keys; a decimal carriage adapted to be released one step by the operation of any of said keys; a totalizer mounted on said decimal carriage; carrying 95 mechanism adapted to coöperate with said totalizer in all of its decimal places; and means operated by said keys to aline said carrying mechanism *seriatim* subsequent to the operation of any key and prior to the 100 escapement of said decimal carriage.

7. In a calculating machine the combination of: a totalizer; a carrying mechanism, said totalizer being adapted to move relatively to said carrying mechanism; a master gear; a set of keys; and means brought 105 into operation upon the actuation of any of said keys and operated by said keys to rotate said master gear a differential amount, aline said carrying mechanism and then move said 110 totalizer relative to said master gear and carrying mechanism.

8. In a calculating machine, the combination of a carrying mechanism including an element for each decimal order, a totalizer moving relatively thereto, and a wedge-shaped aliner for said carrying mechanism said aliner being adapted to contact first with the element of the carrying mechanism in lower order and subsequently with the 120 element of the carrying mechanism in higher order.

9. In a calculating machine the combination of a carrying mechanism including a member for each decimal order, a totalizer 125 moving relatively thereto, a set of numeral keys adapted to insert numbers in said totalizer, and a wedge-shaped aliner adapted

to contact with said carrying members *seriatim* and operated by said keys.

10. In a calculating machine, the combination of a frame, a traveling totalizer, actuating mechanism for inserting numbers therein *seriatim*, a set of transfer gears mounted on said frame and adapted to coöperate with said totalizer in all of its decimal places, an aliner for said transfer gears, said aliner being adapted to rock about an axis parallel to the axis of said transfer gears and having an operating face shaped at an angle to the axis of said transfer gears, the line of said operating face when produced intersecting the axis of said transfer gears at a point to the right of the operating position of said actuating mechanism.

11. In a calculating machine, the combination of a frame, a traveling totalizer, a set of transfer gears mounted on said frame and adapted to coöperate with said totalizer in all of its decimal places, an alining device for said transfer gears, a set of numeral keys, and means operated by said numeral keys to actuate said alining device to aline said transfer gears *seriatim*.

12. In a calculating machine the combination of a frame, a traveling totalizer, a set of keys adapted to insert numbers in said totalizer *seriatim*, a set of transfer gears mounted on said frame and adapted to coöperate with said totalizer in all of its decimal places said transfer gears consisting of a plurality of gears one for each decimal order, and means operated by said keys to aline said transfer gears *seriatim* upon the operation of any of said keys.

13. In a calculating machine, the combination of a set of numeral keys, a decimal carriage adapted to escape one step by the operation of any of said keys, a totalizer mounted on said decimal carriage, a set of transfer gears adapted to coöperate with said totalizer in all of its decimal places, alining devices coöoperating with said transfer gears *seriatim*, and means operated by any of said numeral keys for withdrawing said alining devices from said transfer gears prior to the insertion of a number and bringing said alining devices in operative relation to said transfer gears subsequent to the insertion of a number.

14. In a calculating machine, the combination of a frame, a traveling totalizer, a set of keys adapted to insert numbers in said totalizer, a set of transfer gears mounted on said frame there being one of said gears for each decimal place said gears being adapted to coöperate with said totalizer in all of its decimal places, and means to aline said transfer gears *seriatim* said means being brought into operation by said keys prior to the return of any of said keys to its normal position.

15. In a calculating machine, the combination of a set of numeral keys, a decimal carriage adapted to be released one step by the operation of any of said keys, a totalizer mounted on said decimal carriage, a framework upon which said decimal carriage is adapted to reciprocate, a set of transfer gears rotatably mounted in said framework, any one of said transfer gears being adapted to coöperate with said totalizer in any of its decimal places, and means operated by any of said keys to aline said transfer gears *seriatim* prior to the escapement of said decimal carriage.

16. In a calculating machine, the combination of a set of numeral keys, a framework, a decimal carriage adapted to reciprocate on said framework and also adapted to be released one step by the operation of any of said keys, a totalizer mounted on said decimal carriage, said totalizer including a set of gears, a lock for said totalizer gears, said lock being adapted to be operated by any of said numeral keys, a set of transfer gears rotatably mounted in said framework, any one of said transfer gears being adapted to coöperate with said totalizer in all of its decimal places, and means operated by any of said keys to first unlock said totalizer gears, then to actuate said gears and then to aline said transfer gears *seriatim* prior to the escapement of said decimal carriage.

17. In a calculating machine, the combination of a moving carriage, a set of transfer gears, a totalizer moving relatively thereto in a manner determined by the motion of said moving carriage, a wedge-shaped aliner adapted to contact with a plurality of transfer gears *seriatim* and means to operate said aliner.

18. In a calculating machine, the combination of a set of transfer gears, a totalizer moving relatively thereto, a set of keys, a wedge shaped aliner adapted to contact with a plurality of said transfer gears *seriatim*, and means operated by said keys to actuate said aliner and bring it into contact with said transfer gears *seriatim*, whereby upon operation of the keys the gear of lower order is alined prior to the gear of higher order.

19. In a calculating machine, the combination of a set of numeral keys, a set of transfer gears, a gang of computing wheels traveling relative to said transfer gears and adapted to engage any of said transfer gears, said computing wheels being also adapted to receive numbers inserted into them by any of said keys, an escapement controlling the position of any of said computing wheels and an alining device to aline the return of any of said keys to its said transfer gears and computing wheels *seriatim* prior to the escapement of said

- computing wheels to engage said transfer gears in an additional place, said alining device being also adapted to be withdrawn from its contact with said transfer gears 5 during the operation of any of said numeral keys.
20. In a calculating machine the combination of a set of transfer gears having deep teeth, a set of numeral keys, a wedge-shaped aliner for said transfer gears said aliner being adapted to contact with said transfer gear of lower order prior to its contact with a transfer gear of higher order, and means operated by any of said keys 15 for operating said aliner.
21. In a calculating machine, the combination of a set of transfer gears, a set of numeral keys, a universal member actuated by any of said numeral keys, and an aliner 20 adapted to aline said transfer gears *seriatim* operated by said universal member.
22. In a calculating machine the combination of a totalizer including a set of computing wheels, a set of transfer gears 25 adapted to mesh with said computing wheels and carry tens from a computing wheel of lower order to a computing wheel of higher order, a set of keys, actuating mechanism operated by said keys and adapted to actuate said computing wheels, means to move said totalizer relative to said transfer gears said means being brought into operation upon the actuation of any of 30 said numeral keys, a lock mounted in said totalizer common to all of said computing wheels, and a universal member operated by any of said keys to control said lock.
23. In a calculating machine the combination of: a totalizer, including a set of 40 carrying gears; a set of transfer gears; means to release said totalizer step by step relatively to said transfer gears; a lock for said carrying gears; a set of numeral keys; an aliner for said transfer gears; and a universal member to operate said lock and 45 said aliner, coöperating with all of said keys.
24. In a calculating machine the combination of: a totalizer, including a set of 50 carrying gears; a set of transfer gears; means to release said totalizer step by step relatively to said transfer gears; a lock for said carrying gears; an aliner for said transfer gears; a set of keys; and means coöperating with said keys to operate said lock, aliner and escapement upon the actuation 55 of any of said keys.
25. In a calculating machine the combination of: a totalizer including a set of 60 carrying gears; a master gear to insert numbers therein; a set of transfer gears; means to release said totalizer step by step relatively to said transfer gears; a lock for said carrying gears; an aliner for said
- transfer gears; and a set of key operated 65 levers any one of which serves to operate said lock, master gear, aliner and escapement.
26. In a calculating machine the combination of: a decimal carriage; a totalizer 70 including a set of carrying gears, mounted thereon; a set of transfer gears; means to release said decimal carriage step by step relatively to said transfer gears; a lock for said carrying gears; a lock for said decimal 75 carriage; a set of numeral keys; and means common to all of said keys to lock said decimal carriage and unlock said carrying gears during the operation of any key.
27. In a calculating machine the combination of: a totalizer; a set of transfer gears, said totalizer and transfer gears being adapted to move relatively to each other; a set of numeral keys; and means associated with said transfer gears to limit to 80 a single step their movement as consequent to the single operation of any key.
28. In a calculating machine the combination of: a totalizer; a set of transfer gears, said totalizer and transfer gears being adapted to move relatively to each other; a set of numeral keys; and a set of cams associated with said transfer gears to limit to a single step the movement of said transfer gears consequent to a single operation of any key.
29. In a calculating machine the combination of: a set of carrying gears; a set of transfer gears, coöperating therewith; and a set of spring operated cams coöperating 100 with said transfer gears to thereby prevent their overthrow.
30. In a calculating machine the combination of: a gear; an oscillating cam, having two notches adapted to coöperate with the teeth of said gear; and means to hold said cam in a position where either notch may be engaged by said teeth.
31. In a calculating machine the combination of: a gear; an oscillating cam having 105 two notches adapted to coöperate with the teeth of said gear; and a spring to hold the cam in a position where either notch may be engaged by said teeth.
32. In a calculating machine the combination of: a gear; an oscillating cam having 110 a notch and locking surface adapted to coöperate with the teeth of said gear; and means to hold said cam in a position where said notch may be engaged by said teeth, the parts being so disposed that rotation of said gear will oscillate said cam to a position where said locking surface will prevent further rotation of said gear.
33. In a calculating machine the combination of: a gear; an oscillating cam having 115 two notches and two locking surfaces adapted to coöperate with the teeth of said gear;

and means to hold said cam in a position where either of said notches may be engaged by said teeth, the arrangement being such that said gear may be moved but one tooth in either direction for each oscillation of said cam.

34. In a calculating machine the combination of: a gear; a second gear having a tooth adapted to operate said first gear intermittently, the zero position of said second gear being determined by said tooth being brought into contact with said first gear; and means controlled by said second gear to prevent the motion of said first gear when said second gear is returned to its zero position.

35. In a calculating machine the combination of: a master gear; a carrying gear; a transfer gear operated thereby; and means to prevent the motion of said transfer gear when said carrying gear is rotated to its zero position.

36. In a calculating machine the combination of: a carrying gear; a carrying tooth associated with said carrying gear; a transfer gear adapted to be operated by said carrying tooth; and means preventing the motion of said transfer gear when said carrying tooth is brought into contact therewith.

37. In a calculating machine the combination of: a master gear; a carrying gear; a carrying tooth associated with said carrying gear; a transfer gear adapted to be operated by said carrying tooth; and means controlled by said master gear to prevent motion of said transfer gear when said carrying gear is returned to its zero position.

38. In a calculating machine, the combination of a totalizer including a set of carrying gears, a master gear adapted to insert numbers in said totalizer *seriatim*, a transfer gear adapted to be operated by any of said carrying gears, and an arm connecting said master and transfer gears and adapted to be oscillated by the motion of said master and transfer gears.

39. In a calculating machine the combination of: a master gear; a transfer gear; a carrying gear connecting said master and said transfer gears; and an arm adapted to be rotated in one direction by the teeth of said transfer gear and in the opposite direction by the teeth of said master gear.

40. In a calculating machine the combination of: a master gear; a transfer gear; a carrying gear connecting said master and said transfer gears; and an arm adapted to be rotated in one direction by the teeth of said transfer gear and in the opposite direction by the teeth of said master gear, the arrangement being such that to the passage

of each tooth of the transfer gear, there corresponds one oscillation of said arm. 65

41. In a calculating machine the combination of a frame, a traveling totalizer, an alining device, a set of keys adapted to insert numbers in said totalizer, a set of transfer gears mounted on said frame and adapted to cooperate with said totalizer in all of its decimal places there being one of said transfer gears for each decimal order, and a universal member operated by said keys to operate said alining device and thereby aline said transfer gears *seriatim*. 70 75

42. In a calculating machine the combination of a frame, a traveling totalizer, a set of keys, a differential mechanism adapted to insert numbers in said totalizer said differential mechanism being operated by any of said keys, a set of transfer gears mounted on said frame and adapted to cooperate with said totalizer in all of its decimal places there being one transfer gear for each decimal place of the totalizer, an alining mechanism adapted to aline said transfer gears *seriatim*, and a universal bar operated by way of said keys, said bar operating said alining mechanism subsequent to the operation of said differential mechanism by the action of said keys. 80 85

43. In a calculating machine the combination of a frame, a carriage traveling thereon, an escapement for said carriage, differential mechanism, a master-wheel controlled by said differential mechanism, a totalizer mounted on said carriage, adjustable attaching portions on said totalizer to secure said totalizer to said carriage and permit a lateral adjustment thereon relative to said carriage whereby the zone of action of said master-wheel on said totalizer may be determined, a set of transfer gears mounted in said framing, a gang of computing wheels mounted in said totalizer, the arrangement of computing wheels, transfer gears, carriage and master-wheel being such that when said carriage has determined operative connection between said master-wheel and one 100 105 of said computing wheels the computing wheels of higher order are operatively connected to each other by means of said transfer gears, a lock for said computing wheels, an alining device for said transfer gears 110 115 adapted to contact with the same *seriatim*, a set of numeral keys and mechanism driven by any of said keys to operate said differential mechanism, lock for said computing wheels, alining device and escapement. 120

44. In a calculating machine the combination of a set of numeral keys, a decimal carriage adapted to escape step by step upon the operation of any of said keys, a totalizer mounted on said decimal carriage, carrying mechanism adapted to cooperate with said 125

totalizer in all of its decimal places said carrying mechanism consisting of a plurality of elements one element for each decimal order, and means driven by any of said 5 numeral keys to aline said carrying mechanism *seriatim* whereby the element of said carrying mechanism in the lower decimal order is alined prior to the alinement of the element of said carrying mechanism in the 10 higher decimal order.

45. In a calculating machine the combination of a frame, a traveling totalizer, a set of keys adapted to insert numbers in said totalizer, a carrying mechanism consisting of a plurality of elements one for each decimal order mounted on said frame and adapted to coöperate with said totalizer in all of its decimal places, and means to bring said carrying mechanism 15 into alinement subsequent to the operation of said keys said alining means operating on the elements of said carrying mechanism *seriatim*.

46. In a calculating machine the combination of a set of numeral keys, a decimal carriage adapted to be released step by step by the operation of any of said keys, a totalizer adjustably mounted on said decimal carriage, a carrying mechanism consisting 20

of a plurality of elements one for each decimal place adapted to coöperate with said totalizer in all of its decimal places, and means to aline said carrying mechanism *seriatim* subsequent to the operation of any key and prior to the escapement of said 35 decimal carriage.

47. In a calculating machine, the combination of a set of numeral keys, a decimal carriage adapted to be released step by step after the operation of any of said keys, a 40 totalizer adjustably mounted on said decimal carriage, a carrying mechanism consisting of a plurality of elements one for each decimal place and adapted to coöperate with said totalizer in all of its decimal places 45 and means operated by any of said keys to aline said carrying mechanism *seriatim* subsequent to the operation of any key and prior to the escapement of said decimal carriage.

In witness whereof, I have hereunto subscribed my name in presence of two witnesses.

JOHN BRICKEN.
